UNITED STATES PATENT OFFICE.

SCOTT IRVING DRESSER, OF COATICOOK, QUEBEC, CANADA.

TRUCK.

Application filed June 17, 1922. Serial No. 568,998.

To all whom it may concern:

Be it known that I, SCOTT I. DRESSER, a citizen of the Dominion of Canada, residing at Coaticook, in the Province of Quebec and 5 Dominion of Canada, have invented new and useful Improvements in Trucks, of which the following is a specification.

This invention relates to trucks for handling boxes and the like and has for its object the provision of a novel truck by means of which a warehouseman or the like may handle even heavy boxes, barrels and crates alone, it being a feature of the device that a jack means is provided for lifting the box 15 or other article sufficiently to effect insertion of the truck nose therebeneath.

An important object is the provision of a truck of this character having a novel form of jack forming a permanent part thereof 20 for effecting the necessary lifting action.

A further object is the provision of a device of this character which is provided with means hooking into the box or other article for positively preventing lateral displacement 25 thereof during transportation.

Still another object is the provision of a truck which may be constructed to have either two wheels or a single wheel, depending upon personal preference the action being 30 the same in either event.

An additional object is the provision of a device of this character which will be simple and inexpensive in manufacture, efficient in use, a great time and labor saver and a 35 general improvement in the art.

With the above and other objects and advantages in view the invention consists in the details of construction to be hereinafter more fully described and claimed and illustrated in the accompanying drawings in 40 which:

Figure 1 is a side elevation of one form of my device showing it disposed adjacent the end of a box and in initial position,

45 Figure 2 is a similar view showing the box raised onto the truck and showing the supporting hooks,

Figure 3 is an elevation taken at right angles to Figure 2,

50 Figure 4 is a plan view illustrating the attachment of the supporting arms,

Figure 5 is a longitudinal section through another form,

Figure 6 is a horizontal cross section taken above the caster wheel on Figure 5, 55

Figure 7 is a detail perspective view of one of the structural elements.

Referring more particularly to the drawings and especially to the first form of my device the numeral 10 designates broadly a 60 frame which might be formed integral or which might be formed of a plurality of sections or elements secured together by any desired means such as riveting or welding. This frame includes a horizontally disposed 65 U-shaped lower portion 11 from which rises an inverted U-shaped vertical portion 12 which has the ends of its arms located intermediate the ends of the arms of the portion 11. The numeral 13 designates inclined 70 braces located near the corners of the upper portion 12 for the purpose of reinforcing the same. The lower portion 11 constitutes the nose of the truck and has its upper surface provided with prongs 14 designed to 75 bite into the box, crate, barrel or the like to be handled, so as to prevent slipping.

Journaled beneath the arms of the lower frame member 11 is an axle 15 carrying wheels 16. Extending from the lower frame 80 member 11 at the center thereof is a slotted guide 17 which is formed with bearings engaging the axle 15. The rear side of the right portion of the upper frame member 12 is formed with a bearing 19. 85

Slidable through the guide 17 and bearing 19 is a vertical rod 20 which has its lower end enlarged to define a foot 21 engageable with the floor or other surface over which the truck is to be moved. Carried by this 90 rod above the frame is a jack consisting of a lower sleeve 22 slidably mounted upon the rod and adapted to be held in any adjusted position by means of a set screw 23. Slidable upon the rod above the sleeve 22 is a 95 second sleeve 24 terminating at one side in a tooth 25 designed to bite into the box or crate when a lifting action is to be exerted. Pivotally connected with the sleeve 22 as shown at 26 are upwardly extending links 100 27 with which are pivotally connected the sides of a handle 28 which is pivotally con-

nected as shown at 29 with the opposite sides of the sleeve 24.

The box holding means consists of a yoke 30 designed to be engaged against the rod 20 at the side thereof most remote from the article to be transported, this yoke terminating in loops 31 within which are pivotally engaged eyes 32 formed on the ends of elongated rods 33 terminating in hooks 34 designed to bite into the box or crate at opposite side thereof.

In the operation of the device it will be seen that it is wheeled up to a point immediately against the box or crate as shown in Figure 1 and the jack structure is adjusted along the rod 20 to bring it at the desired height. The operator then moves the handle 28 upwardly to move the tooth 25 downwardly and then forces the truck against the box or crate to make the tooth bite into the material. A subsequent downward push upon the handle 28 will result in causing the sleeve 24 to move upwardly and cause elevation of one end of the box or crate. During this action the foot 21 of course engages the ground or floor to form a rigid support during the jacking action. When the box has been lifted slightly as above described, it is a simple matter to pull the truck away from the box whereupon the box will swing and drag so that its slightly elevated lower edge will engage upon the frame member 11, the prongs 14 preventing slipping. The yoke 30 is placed in position against the rod 20 with the hooks 34 biting into opposite sides of the box or crate. When the operator then pulls back upon the rod 20 the box will be lifted from the ground or floor so that its weight will be borne by the wheels 16. The load may then be easily wheeled or rolled to any place desired.

In the modified form I have shown the truck as having but a single wheel. In this form of the invention I provide a lower frame member 35 and an upper frame member 36 corresponding to the members 11 and 12 of the first described form. The upper frame 36 is provided at the center of its uppermost portion with a bearing 37 corresponding to the bearing 19 but the lower frame is provided with a bearing 38 instead of the guide 17 shown in the first form. I also provide the upper frame 36 with a cross bar 40 provided with a bearing. The numeral 41 designates a caster wheel journaled in a yoke 42 having its trunnion 43 journaled through the bearing 38 and the bearing in the cross bar 40.

The rod 20 of the first described form is replaced, in this instance, by a rod 44 which is slidably mounted through the bearing 37 and which has its lower end branched to define a U-shaped portion 45 which has its arms slidably engaged through guide brackets 46 projecting rearwardly from the cross bar 39.

The rod 44 carries identically the same jack structure as in the first described form and the same box holding hooks are employed.

In the operation of this form of the device it will be seen that the action is the same as in the first form, the only difference being that in this instance the truck has but one wheel as compared with the two previously described.

While I have shown and described the preferred embodiments of the invention it is of course to be understood that I reserve the right to make such changes in the form, construction and arrangement of parts as will not depart from the spirit of the invention or the scope of the subjoined claims.

Having thus described my invention I claim:

1. In a device of the character described, a frame, an axle passing therethrough and carrying wheels, guides on said frame, a rod slidable through said guides and having a forked lower end, a collar adjustably mounted on said rod, a collar slidable on the rod above said first named collar and having a tooth, links pivotally connected with said first named collar and extending upwardly, and a U-shaped lever having its arms pivotally connected with the slidable collar and with the upper ends of said links.

2. A device of the character described comprising a wheeled frame provided with guides, a rod extending through said guides and terminating at its lower end in a bearing foot, and a jack vertically adjustably mounted upon the rod above the frame, and box holding means consisting of a yoke engaging partially about the rod above the jack structure and a pair of rods pivotally connected with the yoke and terminating in hooks adapted to bite into the load.

3. A truck of the character described comprising a frame including a lower horizontally disposed member and a vertically disposed member secured thereto; said frame being wheel supported, a vertically movable rod slidable through guides on the frame members and having its lower end terminating in a bearing foot, box holding means carried by said rod, and a jack structure adjustably mounted upon the rod, said jack consisting of spaced sleeve members, one sleeve member terminating in a tooth, a handle pivotally connected with one sleeve member, and links pivotally connected with the handle and with the other sleeve member.

4. A truck of the character described comprising a frame including a lower horizontally disposed member and a vertically disposed member secured thereto, said frame being wheel supported, a vertically movable rod slidable through guides on the frame members and having its lower end terminating in a bearing foot, box holding means

carried by said rod, and a jack structure adjustably mounted upon the rod, said jack structure consisting of upper and lower sleeve members slidably mounted upon the rod, means for holding the lower sleeve member at an adjusted position, the upper sleeve member being formed with a biting tooth, a handle connected with the upper sleeve member and links pivotally connected with the handle and with opposite sides of the lower sleeve member.

5 In testimony whereof I affix my signature.

SCOTT IRVING DRESSER.
